UNITED STATES PATENT OFFICE

2,601,732

SWIVEL FOR BULLDOZER BLADES

John Adams Thierry, South Milwaukee, Wis., assignor to Bucyrus-Erie Company, South Milwaukee, Wis., a corporation of Delaware

Application December 16, 1946, Serial No. 716,457

2 Claims. (Cl. 37—144)

1

My invention relates to new and useful improvements in swivels for bulldozer blades, and more particularly the blades of angling bulldozers.

In bulldozers of the type to which my invention is more particularly adapted, namely angling bulldozers, a U-shaped frame, surrounds the front end of a tractor, the ends of the two branches of the U being pivoted to the sides of the tractor, usually on or adjacent to the rear axles thereof. The center of the curve of the U is attached to the center of the rear of the blade by means of a joint, which permits the blade to be tilted in a vertical plane and angled in the horizontal plane. An adjustable brace extends from the sides of the U to each end of the blade, where the brace is attachable at various elevations to an arcuate guide on the blade, thus effecting tilting of the blade in a vertical plane. Attaching the rear ends of the braces at various selective positions on the U effects angling of the blade in the horizontal plane.

It is important to have the connection between the U and the blade such that, as the blade is tilted and angled, the face of the blade is always in the same plane relative to the ground. To accomplish this, designers have, in recent years, adopted the use of an intermediate mounting block which is attached to the center of the U-frame by a vertical pin that permits angling, and to the back of the blade by another pin or swivel connection that permits tilting only about an axis perpendicular to the face of the blade. However, this solution has the disadvantages that it is expensive, makes disassembly complicated, and is not sufficiently compact to bring the blade as close to the front of the tractor as is desired.

Accordingly, the principal object of my invention is to improve the connection between the blade and the U, with the following ends in view, namely:

(1) To provide a connection which will tiltably support the blade on an axis which is always at right angles to the blade.

(2) To render this connection more compact, thus bringing the blade closer to the front end of the tractor.

(3) To render more simple and easy the assembling and disassembling of the blade.

(4) To provide a connection in which all independent moving or removable parts other than a single pin between the blade and the supporting U-member are eliminated.

(5) To provide a connection which is simpler, lighter, and cheaper to manufacture.

2

(6) To provide a connection that will furnish a firm and steady mounting for the blade and a snug fitting relationship between the blade, the supporting U-frame, and the connecting pin, in all positions of tilting and angling.

In addition to the objects above stated, I have worked out a number of novel and useful details, which will be readily evident as the description progresses.

10 My invention consists in the novel parts, and in the combination and arrangement thereof, which are defined in the appended claims, and of which one embodiment is exemplified in the accompanying drawings, which are hereinafter particularly described and explained.

15 Throughout the description, the same reference number is applied to the same member or to similar members.

20 Referring now to the accompanying drawings, it will be seen that:

Figure 1 is a plan view of the blade and U-shaped frame of a bulldozer, according to the present invention, the blade being partly in section.

25 Figure 2 is a rear elevation of the blade, taken along the line 2—2 of Figure 1.

Figure 3 is an enlarged diagonal view, from one side rear, partly in section, showing the front central portion of the supporting U-shaped frame, the central portion of the blade, and the connection between them.

30 Figure 4 is a transverse vertical section of said connection, taken along the line 4—4 of Figure 5.

Figure 5 is a longitudinal vertical section of 35 said connection, taken along the line 5—5 of Figure 4.

Figure 6 is a horizontal section, taken along the line 6—6 of Figure 4, showing the connection in a horizontal plane through the upper square portion of the pin.

Figure 7 is a horizontal section, taken along the line 7—7 of Figure 4, showing the connection in a horizontal plane through the intermediate circular portion of the pin.

40 Referring now to Figures 1 and 2, we see that 45 11 represents a conventional U-shaped bulldozer supporting frame which serves to mount the bulldozer blade 12 forwardly of a tractor (not shown). The blade 12 is shown in Figure 3 as a built-up structure consisting of a front moldboard 12a, a longitudinal digging edge 12b, and a backplate 12c mounted on the back of the moldboard by means of longitudinal angle irons 12d and 12e. These details of the blade structure are merely 50 55 one of a number of conventional types of con-

struction, and form no part of my invention. The rear ends 13 of the side arms 14 of the U-frame are usually pivotally connected to the sides of the tractor (not shown) so that the U-frame may be raised and lowered about the horizontal transverse axle of the tractor (not shown). The bulldozer blade 12 is disposed transversely of the frame 11 in advance of the front portion 15 of the U-frame. It is mounted to be swung in a normally vertical plane about the horizontal axis of the attaching means, which constitutes a principal feature of my present invention, as will be described hereinafter.

In order to retain the bulldozer blade in a given position in the horizontal plane, channel braces 16, known to the trade as "landsides," are provided between the side arms 14 and the ends of the bulldozer blade 12. The rear end of each landside 16 carries a pin 17 which is receivable in one of holes 18 longitudinally spaced along each side arm 14. The method of attaching the forward ends of the landsides to the arcuate rails 19 on the blade 12, so as to retain the blade in any given tilted position in the vertical plane, may be as shown and described in U. S. Patent No. 2,308,535, issued January 19, 1943, to Thomas R. Paulsen; or any other comparable means may be employed.

Some conventional means (not shown) must be provided for raising and lowering the blade, about the pivotal connection of the frame to the tractor.

Turning now more particularly to Figures 3 to 5, let us consider the means for securing the blade 12 to the forward portion 15 of the frame 11.

The front portion 15 of frame 11 has a cylindrical abutment 20 with spherical ends 21 and 22 and a vertical cylindrical hole 23 therethrough.

On, and integrally secured to, the rear face of the blade 12, is attaching member 24 which has two rearwardly projecting top and bottom lugs 25 and 26. These lugs are adapted to overlie the spherical ends 21 and 22 of abutment 20, and have vertical holes 27 and 28 respectively which are keyed by pin 29 to hole 23 in abutment 20.

Pin 29 has a cylindrical portion 30 to fit in hole 23 of abutment 20, a square head 31 with sides slightly longer than the diameter of cylindrical portion 30 to fit in hole 27 of lug 25, and square end 32 with sides slightly shorter than the diameter of cylindrical portion 30 to fit in hole 28 of lug 26.

Holes 27 and 28 in lugs 25 and 26 are rectangular in cross section. Their short sides 33 and 34 are perpendicular to the back of the blade and are approximately the same length respectively as the sides of head 31 and end 32 of pin 29 in order to give snug fit and prevent any fore-and-aft tipping of the blade. Their long sides 35 and 36 are somewhat longer than the sides of the pin head and end respectively, in order to permit the blade to tilt about its perpendicular axis. The difference in length is small, however, because the maximum angle of tilt is usually only about 6 degrees.

The top and bottom surfaces of lugs 25 and 26 respectively are cylindrical about the tilting axis of the blade. Pin 29 has a curved cap 38 which overlaps and contacts snugly the top surface of lug 25 in all positions of tilt and thereby prevents dirt from collecting between pin head 31 and the sides of hole 27. Cap 38 also serves to hold up pin 29, keeping head 32 out of wearing contact with spherical surface 21.

The object of squaring the head 31 and the

lower end 32 of pin 29 is two-fold. First, to prevent the cap 38 from rotating out of covering position. Secondly, to afford a surface-contact rather than a line contact between pin 29 and holes 27 and 28 in the blade-lugs 25 and 26, thus insuring the blade against the tipping which would be permitted as a line contact began to wear. But it should be noted that, for these purposes, only the front and rear surfaces of head 31 and end 32 need be flat; and that the first purpose would be fully served, and the second purpose partly served, if only one end of pin 29 were thus treated.

The forward half of the inner surface of lugs 25 and 26 is spherical to register on the spherical ends of abutment 20, but the rear half is cylindrical about the tilting axis of the blade to permit the lugs to be withdrawn from the abutment when the blade is dismantled.

The connection is assembled by simply inserting abutment 20 between the lugs 25 and 26 of member 24 on the back of the blade and then inserting pin 29 through the three holes already described. The pin may be held in place by a cotter-pin (not shown) or other suitable fastening means.

It will be noted that my pin 29 is the only part to be inserted or adjusted in assembly, inasmuch as my invention has eliminated the second pin, pivot plate, or bayonet joint as the case may be commonly used in present machines between the blade and the separate attaching member. Furthermore it will readily be seen that the blade can be assembled and disassembled in normal horizontal position, without it being necessary to turn either it or any other part. Another advantage of this connection is that it is more compact, it being possible to place the blade closer to the supporting frame because of the elimination of any intermediate attaching member with its additional pin or other swivel joint between the blade and the supporting frame.

Having now described and illustrated one form of my invention, I wish it to be understood that my invention is not to be limited to the specific form or arrangement of parts herein described and shown; or specifically covered by my claims.

I claim:

1. In a bulldozer, the combination of: a U-shaped supporting frame; a blade; a pin; a supporting member rigidly mounted on the back of the blade; said member having a hole for receiving a portion of said pin; the supporting frame having a hole for receiving another portion of said pin, and having a spherical bearing surface adjacent this hole; said spherical bearing surface having supporting contact with the underside of said supporting member; and the transverse dimension, parallel to the back of the blade, of one of said holes being materially greater than the corresponding dimension of the portion of the pin within such hole, thereby permitting relative tilting movement of the supporting member and the supporting frame about an axis that is normally perpendicular to the blade and passes through the center of said spherical surface.

2. A bulldozer according to claim 1, further characterized by the fact that said pin has a direct sliding contact with at least one side of one of said holes in a plane parallel to the back of the blade and has direct bearing contact with at least a portion of the wall of the other of said holes, so that the blade is constrained against tipping in at least one direction and direct bearing contact is provided between the supporting member

and the pin as well as between the supporting member and the U-shaped supporting frame.

JOHN ADAMS THIERRY.
